UNITED STATES PATENT OFFICE.

THEODORE LEMBORG, OF CONCORD, NEW YORK, ASSIGNOR TO JOHN SCHUMM, OF CONCORD, NEW YORK.

DESIGN FOR A TOY.

50,445.

Specification for Design.

Patented Oct. 26, 1920.

Application filed November 28, 1919. Serial No. 341,324. Term of patent 7 years.

To all whom it may concern:

Be it known that I, THEODORE LEMBORG, citizen of the United States, and resident of Concord, S. I., in the county of Richmond and State of New York, have invented a new, original, and ornamental Design for a Toy, of which the following is a specification, reference being had to the accompanying drawing, forming part thereof.

The figure is a perspective view of a toy, showing my new design.

I claim:

The ornamental design for a toy, as shown. Signed at New York city, in the county of New York, and State of New York, this 21st day of November, A. D. 1919.

THEODORE LEMBORG.
